WALTER DOUGLAS LA MONT, OF LARCHMONT, NEW YORK, AND ALFRED F. ERNST, OF PASSAIC, NEW JERSEY, ASSIGNORS TO LA MONT CORPORATION, OF NEW YORK, N. Y., A CORPORATION OF NEW YORK.

APPARATUS FOR SUPERHEATING STEAM.

Application filed July 7, 1927. Serial No. 203,904.

This invention relates to the superheating of steam and to superheater and steam generating apparatus. The operation of superheaters presents a considerable problem in heat transfer and in protection of the material of the heater elements, owing to the fact that the flow of steam through the superheater is far from constant. Superheaters consisting of headers or manifolds connected by a series of heating tubes or elements present advantages in construction and placement, but it is difficult to provide for uniform flow through the different tubes, as there is a tendency for some of the tubes to present a shorter path or one of lower resistance and to carry the greater portion of the steam. This is undesirable, first because the heating surface in the tubes which get little or no steam flow is practically wasted, and also because the tubes with low steam flow tend to get very hot, and in some cases may be in danger of burning out.

It is an object of the present invention to provide superheater construction which permits a desired uniformity of steam flow through all of the heater elements or tubes. It is a further object of the invention in its more specific aspects to provide a superheater structure which can be varied with different operating conditions, and also a structure which may be used for steam generation as well as for superheating.

According to the present invention, the flow of steam into or out of the heating tubes or elements is sufficiently restricted so that a pressure is created in the intake manifold or header sufficient to provide a positive distribution and flow through the several elements of the superheater with varying steam outputs. The restrictions may be in connection with the intake ends of the tubes or elements or with the output ends thereof. In either case sufficient back pressure is produced to assure desired distribution.

It is desirable in some installations to provide a construction which can be utilized for the superheating of steam or for the generating of steam by the formation of water films on the inside of the heating tubes. These conditions require restrictions or orifices at the intake ends of the tubes of

quite different magnitudes. Where steam is to be generated a comparatively small orifice is required, whereas when the device is to be used as a superheater a relatively larger orifice is usually desirable. While in its broader aspects the invention is not limited to a superheater construction which can be adjusted for use as a superheater or as a steam generator, in its more specific aspects such a construction is contemplated and consists in a movable tube, which may for example be concentric with an intake manifold or header and fit in the inside thereof provided with one or two orifices. When two orifices are provided one may be of size suitable for the passage of water when the unit is to be used as a generating unit and the other may be of correct size for steam when the unit is to be used as a superheater. Suitable locking means may be provided for holding the orifice tube in the correct position and, of course, more than one size of orifice may be provided. The inner tube may be moved in any suitable manner to bring various orifices into register with the element, but preferably the tube is arranged to rotate within the manifold.

A somewhat different apparatus for obtaining the same control consists in an inner concentric orifice tube with an orifice of sufficient size to be suitable for superheater demands. By partly rotating the tube, a portion only of the orifice may communicate with the tube, thus providing a very gradual and accurate control. Other equivalent arrangements of orifice tubes may of course be used, and are included in this feature of the invention.

The invention will be described in greater detail in connection with the drawings, in which

Fig. 1 is a side elevation, partly in section, of a superheater unit according to the present invention;

Fig. 2 is a cross-section through a modified design;

Figs. 3 and 4 are sections through a header and orifice tubes provided with a plurality of orifices;

Figs. 5 and 6 are sections similar to Fig. 3, through a header and orifice tube provided with a single orifice.

In the construction shown in Fig. 1, an upper header 2 and a lower header 3 are connected by heating tubes or elements 1. The upper header is provided with an orifice tube 4 containing orifices 5 registering with the tops of the heating tubes 1, and of a size such as to provide sufficient back pressure in the manifold or header tube to assure a predetermined distributed steam flow through all 10 the elements.

In the construction shown in Fig. 2, the upper header or manifold 2 is shown without an orifice, and the lower header 3 is provided with an orifice tube 6 containing orifices 7, 15 registering with the lower ends of the tubes 1 and serving to create sufficient back pressure in the tubes themselves and in the manifold 2 to provide for a satisfactory distribution of steam flowing therethrough.

In the foregoing description emphasis has been laid on the possibility of providing uniform flow by means of suitable orifices or restrictions creating sufficient back pressure to assure that some steam flows into all the 25 tubes. In many, if not in most superheaters, a uniform flow of steam through all of the tubes is usually the most desirable operating condition. In some cases, however, where the superheater may extend through various heat 30 zones, it may be desirable to provide for an increased flow of steam through the hotter zones at all times, in order to protect the tubes situated therein. In other cases different controlled non-uniform distributions 35 may be desirable. In its essence, therefore, the present invention may be considered as providing a positive method for assuring a predetermined distribution of steam through the tubes, and is not limited to an arrangement 40 which produces a uniform flow, this being only one, although perhaps the most important distribution which can be effected by means of the present invention.

It is frequently desirable to standardize 45 superheater constructions, and in order to provide a standard construction which is applicable to superheaters with various average steam flows, or which may be used interchangeably for superheater construction and for generator tubes of the types described in 50 La Mont patent, No. 1,545,668, patented July 14, 1925, and La Mont application serial No. 32,064, filed May 22, 1925, it is necessary to provide for varying sizes of orifices, and this 55 may be effected in various ways.

In the construction shown in Figs. 3 and 4, the upper manifold or header 2 is provided with an orifice tube 8 in which are two orifices 9 and 10 of different sizes. By varying 60 the position of the tube 8 in the header, either size orifice may be caused to register with the upper end of the tubes 1. In order to hold the tube 8 in a given position it may advantageously be provided with a pin or

stud 11 which fits into corresponding grooves 65 12 or 13 in the header 2. In Fig. 3, the pin or stud is shown in groove 12 in order to bring orifice 10 in registry with the tube. If it is desired to cause orifice 9 to register with the tube, the tube 8 is turned through 70 a quarter circle so that the stud or pin 11 is permitted to slide into the groove 13. Preferably the grooves extend only a short way into the header 2, as is shown in Fig. 4, so that it is only necessary to withdraw the orifice tube a short distance in order to turn it. 75

Instead of providing a plurality of orifices of different sizes as shown in the construction of Figs. 3 and 4, an orifice tube 14 provided with a single orifice 15 of maximum size may be used, as is shown in the construction in Figs. 5 and 6. By suitably turning this tube a greater or less extent of the orifice 15 may be brought into registry with the tube 1, and this makes possible a 80 gradual continuous variation of orifice size. When a relatively small orifice is required for use in generators, the tube 14 is turned until only a small portion of the orifice 15 registers with the tube 1, as shown in Fig. 90 5. This construction not only provides for an orifice of suitably small size but also directs the stream of water against the sides of the tubes, which aids in film formation. A similar result can of course be obtained 95 in the constructions shown in Figs. 3 and 4 by cutting the orifice 10 at an angle. Other means for providing suitable orifices or restrictions may be used.

In the foregoing description of the preferred embodiment of the invention separate orifices have been shown, and particularly orifices in orifice tubes. The invention of course is, however, not limited to this method of obtaining uniform distribution. The essential conditions are that the resistance of flow into or through the tubes or into the exhaust header should be sufficiently greater than the resistance of flow into and through the intake manifold so 100 that a back pressure is produced therein. With many ordinary sizes of tubes this necessitates a special orifice structure. It should be understood, however, that if the area of aperture of all of the tubes is sufficiently small in comparison with the intake manifold, the tubes themselves will act as orifices and the provision of tubes small enough to produce uniform or any desired predetermined positive disposition of flow 110 115 is included in the present invention.

Having thus described our invention, what is claimed as new is—

1. A heater unit, comprising in combination an intake manifold, an exhaust manifold, tubular heating elements connecting the two, a concentric rotatable liner in the intake manifold provided with at least two 120 125

series of orifices of different sizes and adapted by its rotation to bring into register with the tube ends orifice apertures of varying sizes.

5 2. A heater unit according to claim 1, in which the orifice liner is provided with means for locking the orifice liner in posi-

tions bringing any row of orifices into register with the tube ends.

Signed at New York, New York, this 5th 10
day of July, 1927.
